United States Patent Office.

ALBERT P. SEYMOUR, OF HECLA WORKS, NEW YORK.

Design No. 4,212, dated July 5, 1870.

DESIGN FOR A DRAWER-PULL.

The Schedule referred to in these Letters Patent and making part of the same.

To all whom it may concern:

Be it known that I, ALBERT P. SEYMOUR, of the Hecla Works, in the county of Oneida and State of New York, have invented a new and original Design for a Drawer-Pull, of which the following is a specification.

My design relates to the forming the front of a drawer of six sides, the upper three of which are concave and the lower three convex.

Description of the Accompanying Drawings.

Figure 1 is a front view of my drawer-pull up side down.

Figure 2 is a cross-section through the center of the same.

Figure 3 is a view of the bottom of same.

General Description.

This form of pull has the advantage of avoiding the usual round and oval forms of pulls, and also those forms of pulls composed of flat sides.

At the same time, in this design, all the advantages of the hollow face, common to the old forms of pulls, in affording a convenient and sufficient hold for the

fingers, when pulling out the drawer, are retained, by making the lower sides, A, B, and O, (see fig. 1,) convex.

The upper sides, D, E, and F, are concave.

All six sides being proportioned to the size of the pull, a new and symmetrical form of pull is secured.

This design does not relate to the ornamentation of the sides, nor to forming recessed panels in these sides, such panel-work being old, but to the placing together concave and convex sides, to form a pull, as described.

Claim.

I claim as my invention—

The design for a drawer-pull, which design consists in a spherical angular front, composed of six sides, the upper three of which are concave, and the lower three convex, substantially as herein represented and described.

ALBERT P. SEYMOUR.
